[57] CLAIM

The ornamental design for a pick-up truckbed storage box, as shown and described.

DESCRIPTION

FIG. 1 is a front elevational view of the pick-up truckbed storage box of the present invention;

FIG. 2 is a rear elevational view of the pick-up truckbed storage box of FIG. 1;

FIG. 3 is a left side elevational view of the pick-up truckbed storage box of FIG. 1;

FIG. 4 is a right side elevational view of the pick-up truckbed storage box of FIG. 1;

FIG. 5 is a top plan view of the pick-up truckbed storage box of FIG. 1;

FIG. 6 is a bottom plan view of the pick-up truckbed storage box of FIG. 1; and,

FIG. 7 is a top, front, left side perspective view of the pick-up truckbed storage box of FIG. 1, shown in open position.

The surface(s) or portion(s) of the article not shown in the drawing or described in the specification form(s) no part of the claimed design.
